DESIGN FOR A NOZZLE FOR DRY CHEMICAL
FIRE EXTINGUISHER

Amie La Fountain and Arthur B. Guise, Marinette, Wis., assignors to Ansul Chemical Company, Marinette, Wis., a corporation of Wisconsin

Application March 28, 1946, Serial No. 128,033

Term of patent 14 years

(Cl. D16—2)

To all whom it may concern:

Be it known that we, Amie La Fountain and Arthur B. Guise, citizens of the United States, residing at Marinette, in the county of Marinette and State of Wisconsin, have invented a new, original, and ornamental Design for a Nozzle for Dry Chemical Fire Extinguisher, of which the following is a specification, reference being had to the accompanying drawing, forming a part thereof.

Figure 1 is a side elevational view of the nozzle for dry chemical fire extinguisher showing our design.

Figure 2 is a top plan view of the nozzle,

Figure 3 is a front view of the nozzle, and
Figure 4 is a rear view of the nozzle.

We claim:

The ornamental design for a nozzle for dry chemical fire extinguisher, as shown.

AMIE LA FOUNTAIN.
ARTHUR B. GUISE.
